UNITED STATES PATENT OFFICE.

WILLIAM D. LA RUE, OF PHILADELPHIA, PENNSYLVANIA, ASSIGNOR TO VICTOR TALKING MACHINE COMPANY, A CORPORATION OF NEW JERSEY.

CASE OR BOX.

Application filed October 31, 1921. Serial No. 511,779.

To all whom it may concern:

Be it known that I, WILLIAM D. LA RUE, a citizen of the United States, and a resident of the city of Philadelphia, in the county of Philadelphia and State of Pennsylvania, have invented certain new and useful Improvements in Cases or Boxes, of which the following is a specification.

My invention relates to boxes or cases for holding and protecting articles which are quite susceptible and liable to injury prior to the time when they are desired for use, such, for example, as talking machine styli, cigarettes, matches, sharp instruments, and the like, and more particularly to boxes or cases of the character above indicated which are provided with a holder or a container in which such articles may be mounted, and which is automatically swung upwardly out of the box or case, to such a position that the articles mounted or carried thereby may be conveniently withdrawn therefrom, when the box is opened.

The objects of my invention are to provide a box which when closed will protect all the articles contained therein from injury; in which the articles contained therein are mounted in a predetermined relation within a comparatively small space; in which the said articles are securely retained against accidental displacement within the box or case; from which one article may be readily removed when it is desired for use; to protect the record-engaging tips of talking machine styli and to keep them out of contact with the box or container and out of contact with each other; to provide a relatively rigid hinged box structure in which a carrier or holder, on which talking machine styli may be mounted or carried, will be automatically swung clear of the box or casing to a position where the styli contained therein, are readily accessible and may be easily withdrawn therefrom, when the lid of the box is opened; and to provide a holder in which talking machine styli may be inserted, securely held and withdrawn, without bringing the record-engaging tip thereof, in contact or engagement with the holder.

Other objects of my invention will appear in the specification and claims below.

In the drawings forming a part of this specification and in which the same reference characters are used throughout the

views to designate the same parts, Figure 1 is a plan view of the box when open;

Fig. 2 is a plan view of the box when closed, a part of the lid or cover section being broken away to show the position of the holder and the styli carried thereby;

Fig. 3 is a vertical sectional view taken on the line 3—3 of Fig. 1;

Fig. 4 is a vertical sectional view on the line 4—4 of Fig. 2;

Fig. 5 is a plan view, and Fig. 6 a longitudinal sectional view on the line 6—6 of Fig. 5, of the holder separated from the box structure;

Fig. 7 is an enlarged vertical sectional view of a portion of the hinge by which the cover section, the box section and the holder are hinged together;

Fig. 8 is a fragmentary plan view of a corner of the box showing one of the hinge members thereof; and Fig. 9 is a fragmentary elevational view of the same;

Fig. 10 is a fragmentary view of the corner of the cover showing one of the hinge members thereof; and

Fig. 11 is an elevational view of the same.

It is now common practice, in operating talking machines to reproduce sound from records, to employ styli or needles, the record-engaging tips of which are of very fine expensive wire, swaged into or otherwise secured to a tapered and rounded end of a stiff metallic shank. The record-engaging tips of such needles may be, and commonly are, of tungsten, and, because of their small diameter, these tips are liable to become bent or broken if they are not properly cared for, handled and stored. It is one of the objects of the present invention, to provide a stiff box, preferably of sheet metal, with a container mounted therein, in which such styli may be permanently kept when not in use, and from which they may be readily withdrawn as occasion requires.

The box or case embodying my invention is preferably made of stamped sheet metal, and consists of two parts, one of which is a box member 1 and the other of which is the lid or cover member 2, hinged together along one side thereof, so that the said lid member 2 fits over and around the box member 1. The terms or expressions "cover member" and "box member" are however merely relative, since either the cover or the

box may be made of any suitable size and shape (as for example substantially alike, as in cigarette cases) without departing from the spirit and scope of my invention. The rear wall 3 of the box member 1 is cut away or notched throughout the greater part of its length from the top downwardly to form a cut away portion or recess 4, and for the purpose of providing hinge members 5—5, preferably integral with the said rear wall 3, rising upwardly and outwardly from the lower edge of said recess 4. The free ends of the said hinge members 5—5 are bent into tubular shape for the reception 15 of the pintle 6. These hinge members 5—5 preferably do not fit tightly around the pintle 6 but instead provide bearings in which the pintle may freely rotate. By reason of the outward offset of the hinge members 5—5 (see Fig. 7), the hinge is substantially clear from the vertical face of the rear wall of the box.

The lid 2 is also provided on its rear vertical wall 7 with two similar hinge members 25 8—8, integral with the lid and so located as to fit respectively into the spaces between the hinge members 5 and those portions or ends 3' of the rear wall 3 which are not cut away but are of the full height of the box. 30 These two hinge members 8—8 are also bent into tubular form to receive the pintle 6, but the inside diameter of the tubular portions thereof is such that the pintle 6 fits tightly therein, so that, when the cover or 35 lid member 2 is lifted from the box member 1 and swung on the axis of the hinge, the pintle 6 turns with the cover on its bearings in the hinge members 5—5 of the box, by reason of the frictional engagement between 40 the hinge members 8—8 and the pintle 6.

Also mounted within the box 1, on the pintle 6, is a holder or carrier 9, from the rear edge 10 of which projects a hinge member 11 integral therewith and bent into tubular form to tightly fit around the pintle 6. This hinge member 11 is preferably of a length to substantially fill the space on the 45 pintle 6 between the hinge members 5—5 of the box.

50 The rear edge 10 of the holder 9 is longer than the cut away or recessed portion 4 in the rear wall 3 of the box so that the ends thereof respectively engage the portions 3' 3' of the rear wall after the holder or carrier has been swung on its axis or hinge upwardly through a predetermined angle to prevent the further angular movement thereof as will be more particularly referred to below.

55 The holder or carrier 9 is provided with a plurality of clips 12, each formed by striking upwardly out of the body of the metal sheet holder 9 a pair of tongues 13—13 inclined toward each other and adapted to bear on the top of a stylus 14 placed there-

under. The stylus shown in the drawing, and to contain which the present invention is particularly adapted, consists of a stiff steel shank 15, one end 16 of which is tapered, and from said tapered end 16 coaxially projects the record-engaging tip 17 of fine stiff tungsten wire. This tungsten wire tip 17 is rather delicate and may be readily bent or broken. It is to provide a container in which such styli may be safely stored and from which they may be readily withdrawn for use that the present invention has for its principal object.

On the same side of the holder 9, and in the rear of the clips 12 I provide a longitudinal slightly elevated rib or ridge 18, the same being preferably located substantially midway between the rear edge of the clips 12 and the hinge member 11. The height of said rib or ridge 18 is less than one-half the difference between the diameter of the shank 15 and the tip 17 so that if a stylus were to be placed flatly on the smooth flat surface of the base 9' of the holder 9 the top of the ridge 18 would not reach to or touch the under side of the tungsten tip 17. When, therefore, a stylus 14 is pushed into a clip 12, the tungsten wire tip 17 passes over the top of the ridge 18 without touching it, and the rounded tapered end 16 of the shank abuts against the stop formed by the ridge 18 wedging the shank more firmly against the under side of the resilient tongues 13. If, however, the stylus were to be pushed still further into the clip, the tungsten tip would not be damaged, because the rounded end of the stylus would slide up over the ridge merely.

As above stated, the hinge members 8—8 of the lid or cover and the hinge member 11 of the holder 9, tightly clasp around and grip the pintle 6. The pintle 6, however, does not tightly fit within the hinge members 5—5 on the bottom of the box 1 proper. By reason of this construction, when the lid 2 is raised from the top of the box and is swung on its hinge, the pintle 6 rotates with it. Since the hinge member 11 also tightly grasps or fits around or frictionally engages the pintle 6, the holder 9 moves with the pintle 6. It will be seen then that when the lid 2 is raised, the pintle 6 rotates and with it carries the holder 9 which rises out of the box to bring the styli carried thereby clear of the top of the box, and to a position from which the styli may be readily withdrawn.

But after the holder 9 has swung upwardly through a predetermined angle, that is to say, to substantially the position shown in Fig. 3, the ends 10' on the rear edge 10 of the member 9 will bring up against and engage the ends 3', 3' on the rear wall 3 of the box and this engagement of the member 9 with the said portion of the

rear wall of the box will prevent any further angular motion of the holder on the axis of the pintle, although the lid itself may be swung further back rearwardly as shown in Fig. 3.

It will thus be seen that the lid member and the holder being frictionally mounted on the pintle 6, at first turn together, that by the lifting of the lid, the holder, 10 turning with it, is automatically elevated to a position in which the styli carried by the holder, may be easily withdrawn therefrom, and that after the holder has been so lifted or swung to a position where it engages the ends 3' on the rear wall, the lid may slip on the pintle or the pintle may slip within the hinge member of the holder 9, as the lid is swung further open through a greater angle.

20 If the cover portion and the box portion of the case above described are made substantially alike, either may be considered as the lid and the other the box, but, for the purpose of this invention, that portion 25 of the box which is tightly secured to the pintle and moves the pintle and the holder is to be considered as the lid.

It must also be apparent that for the successful operation of the device, it is only 30 necessary that the pintle be frictionally engaged by one of the three elements or parts of the case. Thus, the pintle 6 may be positively secured to the lid so as to move positively with it, while the holder frictionally engages the pintle or, on the other hand, the holder may be positively secured to the pintle to turn therewith and the lid frictionally mounted on the pintle. Such changes and modifications are fully within 40 the aim and scope of my invention.

Having thus described my invention, what I claim and desire to protect by Letters Patent of the United States is:

1. In a container, the combination of a 45 box section provided with a hinge member, a pintle mounted to freely oscillate on its axis in said hinge member, a cover having a hinge member in tight frictional engagement with said pintle, and a holder 50 having a hinge member also in tight frictional engagement with said pintle whereby when said cover is raised from said box section said pintle turns therewith and said holder is lifted out of or above the edge 55 of said box section by reason of the frictional engagement between the holder and said pintle.

2. In a carrier for holding small articles, a box comprising two sections together 60 forming a box section and a cover section, a hinge including a pintle for connecting said sections together and a holder between said box sections and also mounted on said pintle, said pintle being free to rotate with respect to one of said box sections and be-

ing secured to the other of said sections so as to rotate on its axis therewith, said holder being in relatively tight frictional engagement with said pintle, whereby when said box sections are turned on said hinge, 70 said holder moves about the axis of the said hinge with that one of said members to which said pintle is secured to rotate.

3. In a container, the combination of a box section provided with a hinge member, a 75 pintle mounted to freely rotate on its axis in said hinge member, a cover tightly mounted on said pintle to cause said pintle to rotate therewith, a holder having a hinge member in tight frictional engagement with said pintle whereby when said cover is raised, said pintle turns therewith and said holder is lifted on the axis of said pintle out of and above the edges of said box section, and means to limit the angular movement of said 80 holder with respect to said box section.

4. In a container, the combination of a pintle, a pair of box members, and a holder member mounted on said pintle, said pintle being free to rotate with respect to one of 90 said box members, means to secure the other of said box members and said holder member to said pintle to rotate together, said means including a tight frictional connection between said two last mentioned members and 95 said pintle.

5. In a container, the combination of a pintle, a pair of box members, a holder member mounted on said pintle, said pintle being free to rotate with respect to one of said 100 box members, means to secure the other of said box members and said holder member to said pintle to rotate together, said means including a tight frictional connection between said two last mentioned members and said 105 pintle, and a stop to limit the angular movement of said holder member with respect to that box member in which said pintle is freely rotatable.

6. In a container, a pintle, a pair of box 110 members mounted on said pintle, and a carrier or holder frictionally mounted on said pintle between the said box members, said pintle being tightly secured to one of said box members to move therewith, and freely 115 rotatable with respect to the other of said box members.

7. In a container, a pintle, a pair of box members mounted on said pintle, a carrier or holder frictionally mounted on said 120 pintle between the said box members, said pintle being tightly connected to one of said box members to move therewith, and freely rotatable with respect to the other of said box members, and a stop on that box member 125 with respect to which said pintle is movable, to limit the angular movement of said holder or carrier with respect thereto.

8. In a holder for talking machine styli, the combination of a base, resilient means

carried by said base and a projection on the same side of said base as said resilient means and spaced slightly from said resilient means whereby when the tapered portion of a 5 stylus is placed adjacent said base under said resilient means and said stylus is pushed longitudinally, the tapered portion of said stylus bears against said projection and the said shank is held firmly pressed against the 10 under side of said resilient means.

9. In a holder for a talking machine stylus having a cylindrical shank, a tapered coaxial end and a record-engaging tip extending coaxially from said end, the combination of a 15 base, resilient means carried by said base and a projection on the same side of said

base as said resilient means, spaced slightly from said resilient means and of a height less than one-half the difference between the diameters of said shank and tip, whereby when the tapered end of said stylus is placed under said resilient means and said stylus is pushed longitudinally, the said tip passes over said projection without touching it, the said tapered end of the stylus slides 20 over the said projection, and the shank is held firmly pressed against the under side of said resilient means.

In witness whereof, I have hereunto set my hand this 27th day of October, 1921.

WILLIAM D. LA RUE.
